CLOSURE ASSEMBLY

Sumner Wiltse, Detroit, Mich., assignor to Vibraseal Corporation, Detroit, Mich., a corporation of Michigan

Application April 16, 1945, Serial No. 588,560

5 Claims. (Cl. 220—39)

1

This invention relates generally to closures and refers more particularly to improvements in closures for openings, passages and ports subjected to fluid under pressure.

In the manufacture of pneumatic or hydraulic equipment having parts provided with internal passages or ports, it is customary to form the latter by drilling into the parts from the outer sides of the latter. It becomes necessary, therefore, to plug the outer ends of the drilled holes and difficulty is often experienced in accomplishing this result in a manner to insure obtaining a fluid-tight joint over long periods of use.

The present invention overcomes the above difficulty by providing a closure assembly having means responsive to installation of the closure to effectively seal the joint between the closure and adjacent walls of the opening to be plugged by the closure assembly.

Another object of this invention is to provide a closure assembly having sealing means so constructed and arranged that fluid under pressure in the passage or port closed by the assembly tends to increase the sealing pressure.

A further object of this invention is to provide a closure assembly composed of a relatively few simple parts capable of being inexpensively manufactured, assembled and installed.

The foregoing as well as other objects will be made more apparent as this description proceeds, especially when considered in connection with the accompanying drawing, wherein—

Figure 1 is a longitudinal sectional view of a part having a closure assembly constructed in accordance with this invention;

Figure 2 is a sectional view through the parts having a passage to be closed by the closure assembly;

Figure 3 is an exploded sectional view of the closure assembly shown in Figure 1;

Figure 4 is a view similar to Figure 1 showing a modified form of closure assembly;

Figure 5 is a sectional view of the part having a passage to be closed by the assembly shown in Figure 4; and

Figure 6 is a view similar to Figure 3 of the closure assembly shown in Figure 4.

Referring first to the embodiment of the invention shown in Figures 1 to 3 inclusive it will be noted that the reference character 10 indicates a part having an open ended passage 11 adapted to be closed and sealed against the escape of fluid through the open end thereof. The outer end portion 12 of the passage is of enlarged diameter

2

and is internally threaded to enable securing a closure assembly 13 therein.

The closure assembly comprises a fitting 14, a thimble or generally cup-shaped member 15 and a deformable ring 16. The fitting 14 is in the form of a sleeve having a tubular portion 17 adapted to project into the enlarged outer end 12 of the passage 11 and externally threaded for coaction with the internal threads in the passage 10 to secure the fitting to the part 10. The outer end of the fitting is provided with an enlarged head 18 forming a shoulder 19 for abutting engagement with the outer surface of the part 10 when the fitting is in assembled relation with the passage 11. The length of the fitting is predetermined with reference to the length of the portion 12 of the passage 11 so that when the fitting is in assembled relation with the passage, the inner end 19 of the fitting is spaced axially 15 outwardly from the annular shoulder 21 in the passage 11 and forms an annular groove 22. The shoulder 21 and end 19 of the fitting are tapered to provide the groove with converging opposite side walls.

25 The thimble or cup-shaped member 15 is preferably formed of a ductile material such, for example, as copper, brass, aluminum or alloys containing these metals. In any event, the member 15 is formed of a material capable of being deformed without damage and is provided with an outwardly extending annular marginal flange 23 at the free edge thereof. The member 15 is adapted to be positioned in the passage 11 at the inner end of the fitting 14 with the marginal flange 23 in juxtaposition to the inner end 19 of the fitting.

30 The ring 16 is also formed of a deformable material such, for example, as rubber, synthetic rubber or rubber-like compositions which are preferably impervious to hydrocarbons, oils and the like. The internal diameter of the ring approximates the external diameter of the member 15 and in actual practice is somewhat less than the latter diameter so as to frictionally engage 35 the exterior surface of this member. The opposite sides 24 of the ring converge from the inner surface of the ring and the length of the ring is predetermined to fit in the annular groove 22.

35 In assembling the several parts of the closure 50 13, the ring is sleeved on the member 15 and the latter is introduced into the passage 11 with the inner tapered surface 24 abutting the annular shoulder 21. The fitting 14 is threaded into the enlarged portion 12 of the passage and the inner 55 end of the fitting abuts the flange 23 on the

thimble or cup-shaped member 15. Upon continued axial movement of the fitting 14, the flange 23 is bent inwardly and the resilient ring 16 is placed under compression in the groove 22. The construction is such that when the fitting is in its final position shown in Figure 1 of the drawing, the opposite converging sides 24 of the ring 16 respectively intimately engage the annular shoulder 21 and the adjacent end 19 of the fitting to form a continuous fluid-tight joint therebetween. Inasmuch as the material from which the ring 16 is formed is relatively non-compressible, it follows that the periphery of the ring is expanded into intimate contact with the annular base of the groove 22 and the inner surface of the ring is contracted against the member 15. Inasmuch as the member 15 is formed of a relatively soft material it follows that the portion of the member engaged by the ring is deformed or contracted in the manner indicated by the reference character 25 and provides a continuous annular seal around the member 15. The general arrangement is such that fluid under pressure in the passage 11 tending to escape past the sealing ring 16 merely increases the sealing pressure and improves the efficiency of the seal.

The embodiment of the invention shown in Figures 4 to 6 inclusive is similar to the construction shown in Figures 1 to 3 inclusive of the drawing and, accordingly, corresponding parts of the two embodiments are indicated by the same reference characters. It will be noted, however, that the closure assembly featured in Figures 4 to 6 inclusive comprises an additional part in the form of a metal ring 26 formed of a ductile material similar to the member 15 and having an internal diameter predetermined to enable the same to be sleeved on the member 15 at the inner sides of the resilient ring 16. The ring 26 is formed with a radially outwardly extending flange 27 at the inner edge thereof for engagement with the shoulder 21 on the part 10.

The above construction is such that the ring 26 is deformed in response to axial inward movement of the fitting 14 and forms a protective retainer for the portion of the ring which is exposed to the fluid under pressure in the passage 11. In other words the ring 26 serves to distribute the forces applied to the ring by the fluid under pressure in the passage 11 over a greater area of the ring. It will also be noted that the resilient ring 16 is deformed to contact the annular shoulder 21 radially outwardly of the flange 27 and to contact the member 15 axially outwardly from the outer edge of the ring 26 so that any fluid escaping past the ring 26 is interrupted by the resilient sealing ring 16.

It will further be noted that the fitting 14 shown in Figures 4 to 6 of the drawing differs from the fitting shown in Figures 1 to 3 inclusive of the drawing in that the head 18 is omitted and the bore through the fitting is formed with a polygonally shaped portion 28 for cooperation with a suitable wrench or tool to enable convenient manipulation of the fitting. With the above noted exceptions, the two closure assemblies are identical and operate in the same general manner to effectively seal a port, opening or passage in a part of a fluid pressure device.

What I claim as my invention is:

1. A closure assembly for an open ended passage in a part, comprising a fitting having a portion insertable into the passage through the open end of the latter and attachable to the part, a cup-shaped member of deformable material

adapted to assume a position in the passage at the inner end of the fitting and having a generally radially outwardly extending flange adjacent the inner end of the fitting, an internal annular shoulder in the passage at the inner side of the flange, a resilient ring of relatively non-compressible material sleeved on the cup-shaped member and positioned between the shoulder and flange, the shoulder and inner end of the fitting converging in a general radial outward direction, whereby movement of the fitting axially inwardly of the passage bends the flange on the cup-shaped member axially inwardly against the adjacent side of the ring to place the latter under compression and contracts the ring against the cup-shaped member with sufficient force to correspondingly contract the adjacent surface of the latter member.

2. A closure assembly for an open ended passage in a part, comprising a fitting having a portion insertable into the passage through the open end of the latter and attachable to the part, a cup-shaped member of deformable material adapted to assume a position in the passage at the inner end of the fitting and having a generally radially outwardly extending flange adjacent the inner end of the fitting, an internal annular shoulder in the passage at the inner side of the flange, the shoulder and inner end of the fitting converging in a general radial outward direction, sealing means surrounding the cup-shaped member between the shoulder and flange on the latter member, said sealing means comprising a resilient ring of relatively non-deformable material and having opposite sides converging in a general radial outward direction, whereby movement of the fitting axially inwardly of the passage bends the flange on the cup-shaped member axially inwardly against the adjacent side of the ring to place the latter under compression and contracts the ring against the cup-shaped member with sufficient force to correspondingly contract the adjacent surface of the latter member.

3. A closure assembly for an opening in a part, comprising a fitting attachable to the part and having a portion adapted to extend into the opening, a cup-shaped member adapted to assume a position in the opening at the inner end of the fitting and having a generally radially outwardly extending marginal flange abutting the inner end of the fitting, an internal annular shoulder in the opening cooperating with the marginal flange on the cup-shaped member to form an annular groove, a resilient deformable ring sleeved on the cup-shaped member and held under compression in the groove and against the adjacent surface of the member, and a metal protecting ring positioned on the cup shaped member at the inner side of the resilient ring.

4. A closure assembly for an open ended passage in a part, comprising a fitting having a portion insertable into the passage through the open end of the latter and attachable to the part, a cup-shaped member of deformable material adapted to assume a position in the passage at the inner end of the fitting and having a generally radially outwardly extending flange adjacent the inner end of the fitting, an internal annular shoulder in the passage at the inner side of the flange, a resilient deformable ring of relatively non-compressible material sleeved on the cup-shaped member and held under compression between the flange, shoulder and cup-shaped member, and a deformable metal ring having a

portion extending between the shoulder and resilient ring and having another portion projecting between the inner surface of the resilient ring and adjacent surface of the member.

5. A closure assembly for a passage in a part, comprising a shoulder within said passage, an outwardly opening cup-shaped member within said passage and having a lateral flange spaced from and cooperating with said shoulder to provide an annular groove, said cup-shaped member being provided beside said flange with an annular groove in opposed relation to the annular groove aforesaid, a ring of resilient material filling completely and bearing firmly against the walls of the opposed grooves, opposite walls of the first mentioned groove being relatively movable and coacting to maintain a firm engagement of the ring with the walls of both grooves, and means for adjusting one of the relatively movable

walls of said first mentioned groove, including a fitting adjustably connected to the part aforesaid.
